(57) **CLAIM**

The ornamental design for the single shot loading tool, as shown.

DESCRIPTION

FIG. 1: is a perspective view of the embodiment of the single shot loading tool; and,

FIG. 2: is a perspective view of the single shot loading tool engaging a front portion of the cartridge which is aligned for reception into a firearm.

The broken line showing in FIGS. 1 and 2 is included for the purpose of illustrating environment and forms no part of the claimed design.
